UNITED STATES PATENT OFFICE

170,348

PILLOW DOLL

Hilliard Aronov, Montgomery, Ala., assignor to Fabric's Inc., Montgomery, Ala.

Application May 7, 1953, Serial No. 24,895

Term of patent 14 years

(Cl. D34—4)

To all whom it may concern:

Be it known that I, Hilliard Aronov, a citizen of the United States, residing at Montgomery, in the county of Montgomery and State of Alabama, have invented a new, original, and ornamental Design for a Pillow Doll, of which the following is a specification, reference being had to the accompanying drawing, forming part thereof.

I claim:

The ornamental design for a pillow doll, as shown.

HILLIARD ARONOV.
